[57] **CLAIM**

The ornamental design for a newspaper vending machine, substantially as shown and described.

DESCRIPTION

FIG. 1 is a front and top-left perspective view of a newspaper vending machine showing my new design.

FIG. 2 is a front elevational view thereof;

FIG. 3 is a right side elevational view thereof, a portion of the top right corner shown broken-away for clarity of illustration;

FIG. 4 is a rear elevational view thereof;

FIG. 5 is a top plan view thereof, the bottom being substantially a mirror image thereof.

FIG. 2

FIG. 3
